Primary Examiner — Karen S Acker*Assistant Examiner* — Jasmine Mlinarcik(74) *Attorney, Agent, or Firm* — Arash Behravesh;
Mannava & Kang, P.C.(57) **CLAIM**

The ornamental design for a hat, as shown and described.

DESCRIPTION

FIG. 1 is a perspective view of a hat, showing a new design; and,

FIG. 2 is a front view thereof.

The broken lines immediately adjacent to the solid line edges of the claim depict the boundaries of the claim and form no part thereof. All other broken lines depict environmental structure that forms no part of the claimed design.
